UNITED STATES PATENT OFFICE.

FRANCIS M. CONGILL, OF DES MOINES, IOWA.

PLASTERER'S CORNER-STRIP.

1,019,951.

Specification of Letters Patent. Patented Mar. 12, 1912.

Application filed November 5, 1910. Serial No. 590,903.

To all whom it may concern:

Be it known that I, FRANCIS M. CONGILL, a citizen of the United States, residing at Des Moines, in the county of Polk and State of Iowa, have invented a certain new and useful Plasterer's Corner-Strip, of which the following is a specification.

One of the great objections to the use of wooden lath and plaster in buildings is that the wet plaster expands the lath and studding to which the lath is attached and then when the plaster and lath and studding dry the plaster separates at the corners and unsightly cracks are thereby formed.

My object is to provide a plasterer's corner strip of simple, durable and inexpensive construction that may be placed in the corners on the laths and that will receive the plaster and hold the plaster firmly together at the corners so that the contraction of the laths will not contract plaster at the corners.

More specifically it is my object to provide a plasterer's corner strip so arranged that the plaster applied first to one wall and then to the other at the corner will be firmly united and held together by the corner strip in such a manner as to reduce the tendency of the plaster to separate at the corner.

My invention consists in certain details, in the construction, arrangement and combination of the various parts of the device, whereby the objects contemplated are attained, as hereinafter more fully set forth, pointed out in my claim and illustrated in the accompanying drawings, in which:

Figure 1 shows a perspective view of a portion of a plasterer's corner strip embodying my invention, and Fig. 2 shows a detail, horizontal, sectional view of a portion of a building having my improved corner strip applied thereto as in use.

Referring to the accompanying drawings, I have used the reference numeral 10 to indicate studding for a building and 11 laths secured to the studding. In applying the laths when my improved strips are to be used, I first place the laths on one side wall, as shown at the left of the sheet, and I then place the corner strip in position and finally apply the laths upon the wall, as shown at the top of the sheet. The advantages of this arrangement will be set forth herein-after. My improved corner strip comprises a single piece of sheet metal doubled at its central portion at 12. The sides of this doubled portion stand slightly spaced apart

at 13. One of the sides beyond the doubled portion is applied as indicated at 14 and the other side is extended at right angles as indicated at 15. In both of the parts 14 and 15 is a series of nail openings 16 and between the nail openings is a series of pairs of larger openings 17 for plaster. I preferably make the corner strips of strong sheet metal. The space between the part 15 and the edge of the doubled portion 12 is substantially the same as the thickness of an ordinary lath as shown in Fig. 1.

In practical use, I apply my improvement to a building as follows: First, the laths are attached to the studding on one wall in the ordinary manner. I have placed a corner strip in position with the doubled edge thereof in engagement with a studding on the adjacent wall. In this way the corner strip is made to stand with the part 15 properly spaced apart from the studding of the wall adjacent to the laths that have already been placed in position. After this has been done I place the laths on the said adjacent wall under the part 15 of the strip and I then secure both the strip and the laths by nails 18 extending through the strip and laths into the adjacent studding. Then the plaster is placed on the walls and the corner strips are covered by the plaster. Some of the plaster will enter the space 13 in the doubled portion of the corner strip and the plaster will also pass through the openings 17 between the laths and become keyed to the corner strip. In this way the plaster on one wall will become thoroughly united with the plaster on the adjacent wall at the corner.

Assuming that the plaster and laths contract after the plaster dries it is obvious that the spring metal will permit only a very slight movement of the part 15 relative to the part 14, not enough to permit the plaster to crack, and the contraction of the lath and plaster is therefore equally distributed along both walls adjacent to the corner in such a manner as to avoid cracking.

In applying plaster to a wall it is the ordinary practice to first apply it to one wall adjacent to the corners and then apply it to the other wall near the corner. Plaster is usually mixed with hair or other binding material to hold it together to prevent cracking. Obviously the binding material on one of the walls at the corner will ordinarily not unite with the plaster of the opposite

wall when it is put together in the manner above described so that there is a tendency for the plaster to separate at the corner on account of the fact that there is no binding material extending from one wall to the other. My improvement serves as a substitute for such binding material for the reason that the plaster is firmly keyed to the corner strip, first on one wall and then on the other at the corner, thus causing the two layers of plaster on the adjacent walls to be firmly and securely united in such a manner as to prevent cracking. It is however desirable to provide for a slight amount of elasticity in the corner strips in order to prevent the corner strips from tearing apart from one wall to the other during the expansion or contraction of the studding and lath. By my improved corner strip this slight elasticity is provided for and yet the parts are so arranged that there may be sufficient elasticity without danger of cracking the plaster when the parts 14 and 15 spread slightly on account of the expansion

or contraction of the studding to which they 25 are attached.

I claim as my invention:

A plasterer's corner strip formed of a single piece of sheet metal folded double at its central portion with the sides of said folded 30 portion spaced slightly apart from each other to receive plaster between them, one end of said strip being bent at right angles to the other end and to said folded portion, the width of said folded portion being such, 35 that when the folded end thereof is placed against a wall, an end of a lath can be conveniently received between the bent end of the strip and the wall, the ends of said strip being provided with openings to receive fastening devices and with openings to receive plaster for keying plaster to the strip and to laths.

Des Moines, Iowa, August 16, 1910.

FRANCIS M. CONGILL.
